(57) **CLAIM**

The ornamental design for an speaker baffle, as shown and described.

DESCRIPTION

FIG. 1 is a front perspective view of a speaker baffle showing the new design in a first embodiment;

FIG. 2 is a rear elevation view thereof;

FIG. 3 is a left side elevation view thereof;

FIG. 4 is a right-side elevation view thereof;

FIG. 5 is a top plan view thereof;

FIG. 6 is a front elevation view thereof;

FIG. 7 is a rear perspective view thereof;

FIG. 8 is a front perspective view thereof, shown in an environment of use;

FIG. 9 is a front perspective view of the speaker baffle showing the new design in a second embodiment;

FIG. 10 is a rear elevation view thereof;

FIG. 11 is a left side elevation view;

FIG. 12 is a right-side elevation view thereof;

FIG. 13 is a top plan view thereof, the bottom plan view being a mirror image thereof;

FIG. 14 is a front elevation view thereof;

FIG. 15 is a rear perspective view thereof; and,

FIG. 16 is a front perspective view thereof, shown in an environment of use.

The broken lines showing an audio device in FIGS. 8 and 16 depict environmental subject matter that forms no part of the claimed design.

1 Claim, 12 Drawing Sheets
